UNITED STATES PATENT OFFICE.

VICTOR BONNET, HIPPOLYTE LISSAGARAY, ARMAND RICHARD, AND ALFRED RICHARD, OF PARIS, FRANCE.

DEVICE FOR EXHIBITING PICTURES.

SPECIFICATION forming part of Letters Patent No. 399,127, dated March 5, 1889.

Application filed May 1, 1888. Serial No. 272,468. (No model.) Patented in France December 10, 1887, No. 18,752; in Belgium December 13, 1887, No. 79,897, and in England December 16, 1887, No. 17,611.

To all whom it may concern:

Be it known that we, VICTOR BONNET, HIPPOLYTE LISSAGARAY, ARMAND RICHARD, and ALFRED RICHARD, all citizens of the Republic of France, and all residing at the city of Paris, in said Republic of France, have invented a new and useful Device for Exhibiting Pictures, (for which we have obtained Letters Patent of the said Republic of France, No. 18,752, dated December 10, 1887; of Belgium, No. 79,897, dated December 13, 1887, and of England, No. 17,611, dated December 16, 1887,) of which the following is a specification.

15 The object of the invention is to produce such a device as will more fully and easily exhibit photographs, prints, and pictures to the view of one or more persons upon the dropping of a coin into the cash-box, as hereinafter specified; and the invention consists 20 in the details of combination and construction, substantially as illustrated in the drawings, hereinafter described, and subsequently pointed out in the claim.

25 Figure 1 is a front view, in elevation, illustrating our new invention for exhibiting pictures. Fig. 2 is a vertical section of the same on a plane parallel to the front view in Fig. 1, and taken upon the line 5 6 of Fig. 4. Fig. 30 3 is a plan section of the same on the line 1 2 of Fig. 2. Fig. 4 is a vertical section taken on a plane at right angles to the plane of Fig. 2 and upon the line 3 4 of said Fig. 2. Figs. 5 and 6 are other sectional views illustrating 35 a modification of the same invention.

The mechanism of our invention is inclosed 40 within a case. (Designated by a^x .) Within this case is journaled a shaft. (Designated by a'' .) Upon this shaft are mounted a disk-wheel, 45 designated by a , and a notched wheel. (Designated by a' .) Another shaft (designated by b'' .) is also journaled within said case. Upon this are mounted the wheels b and b' . The wheel b' is an ordinary spur-wheel; but the 50 wheel b has only one tooth, which engages the notches of the wheel a' . Still another shaft (designated by c'') is journaled within said cover. All these shafts are, as illustrated, arranged one above another, c'' being

the lowest, and on it are mounted the pulley 50 c' and the spur-wheel c , which spur-wheel meshes into the pinion b' upon the shaft b'' . A shaft (designated by d') is journaled within the top of the said case. Upon this is mounted the pulley d . Around this pulley is wound 55 a cord, e , which, passing over the guide-wheel e' , is wound two or three times around the pulley c' , and, passing over the pulley e^2 , is finally tied to the weight p . A lever (designated by l) is pivoted at l^x . The 60 longer end of this lever l is placed directly under the conduit o' . Its shorter end bears on one end of the lever g , which is pivoted at g^x . To the other end of this lever g is pivoted the lower ends of the upright bar h . 65 The upper end of this bar is pivoted to the bell-crank $h' h''$. This bell-crank is pivoted at h^x , and has a hook on the end of its arm h'' , which engages the shank of the knob m . This knob, which projects without the said 70 case, is also attached to the wheel d and works in the circular slot d^x . At o is an opening, into which coins are to be put, which coins are conducted downwardly by the conduit o' . The pictures to be exhibited are arranged radially 75 on the disk-wheel a , and are to be seen by the spectator looking in at n , where a transparent prism or lens may be placed for that purpose. If the pictures be exhibited in daylight, the illumination may be made sufficient 80 by the use of mirrors, but if it be at night a light (designated by r) may be used for illumination. This may be an electric light sustained by the batteries p^x ; or it may be any 85 other light of sufficient strength.

To use this apparatus, the keeper in charge draws the knob m upward in the slot d , so as to bring the various parts into the position illustrated in Fig. 2. Then one of the pictures on the wheel a will be in sight of the observer 90 looking in at n . If, then, a coin be dropped in at o , it will fall down through the conduit o' upon the long end of the lever l . This coin, partly by its weight and partly by its impulse, will cause this end of the lever to tilt 95 downward and the other end to tilt up correspondingly. This releases the lever g , the bar h , and their accompanying mechanism, so

that the weight p can pull the cord e a little downward. This turns the wheels c and c' upon the shaft c'' . The wheel c turns the wheels b and b' upon the shaft b'' . The wheel 5 b , with its one tooth engaging a notch of the wheel a' , turns it and the disk-wheel a far enough to carry the picture thereon which was in view out of sight and display another. The operator then pulls up the knob m again, 10 drawing up the weight, replacing the levers, turning the wheels c , c' , b' , and b backward, and replacing the mechanism into the position illustrated in Fig. 2. The construction of the wheels a' and b is such that when the 15 wheel b moves one way its tooth carries the wheel a' forward one notch, which is just far enough to present a new picture for each move, and in moving the other way the tooth of the wheel b passes the wheel a' without 20 moving it, so that the wheel a' and the wheel a are prompted forward in one direction by the motions of the wheel b , and so that all the pictures on the wheel a will be successively brought into view by dropping in one coin 25 after another. The coins each time fall off the lever l into the drawer x .

In Figs. 5 and 6 a modification of our invention is illustrated. By drawing the rail t the cord u is pulled, and, acting on the mechanism comprising the bell-crank v , the cord u' , the lever v' , the cord e' , and the lever s , sets a pawl (not here shown) back one notch on the ratchet-wheel c' and draws up the weight p a little. As soon as a coin is dropped in it 35 falls down through the conduit o' , drops into one of the pockets q' of the wheel g , and causes the wheel to revolve a little. This moves the levers r' and r'' , which, operating upon the rod s^x , lever r'' , rod s' , lever s , and 40 spring w , releases the mechanism, so that the weight p can pull down the cord e a little, and, turning the wheel c , as before described, presents another picture to the spectator. When the coin has fallen out of the wheel g ,

the mechanism is returned to its original position by pulling the bar t , as before described. 45

What we claim as our invention, and desire to secure by Letters Patent, is—

The combination, with the case a^x , the disk-wheel a , mounted upon a shaft, a'' , journaled within said case, the slotted wheel a' , mounted upon the same shaft, the one-toothed wheel b , mounted on a shaft, b'' , journaled within said case and engaging the slotted wheel a' , the wheel b' , mounted upon the same shaft with 50 the wheel b and meshing into the wheel c , the wheel c , mounted upon a shaft, c'' , journaled within said case and meshing into the wheel b' , the wheel c' , mounted upon the same shaft with the wheel c , the shaft d' , journaled 55 within said case, the wheel d , mounted upon the shaft d' , the cord e , wrapped upon said wheel d , extending over the guide-wheel e' , journaled in bearings in said case, the pulley c' and the guide-wheel e' , journaled on bearings in said case and finally attached to the weight p , and the weight p , attached to the cord e within said case, of the conduit o' within 60 said case, the lever l , pivoted at l^x within said case extending with one end under the conduit o' to receive coins falling therefrom and 65 engaging the lever g with its other end, the lever g , pivoted at g^x within said case, engaging said lever l and pivotally attached to the rod h , the rod h , attached to said lever g and 70 the bell-crank h' , the bell-crank h' , pivoted to h^x within said case and attached to the rod h and the said wheel d , and the knob m , attached to the wheel d and moving in a slot, 75 d^x , in said frame a^x , all substantially as and 80 for the purpose set forth.

VICTOR BONNET.
